METHOD AND APPARATUS FOR CONTROLLING FURNACE COMBUSTION

Henry Wilbur Paret, Jr., Pittsburgh, Pa.

Application November 4, 1937, Serial No. 172,683

19 Claims. (Cl. 263—15)

This invention pertains to improved methods of and apparatus for controlling combustion in a furnace.

In one aspect, my invention pertains particularly to controlling combustion in or the flame characteristics of a heating, reheating, and/or melting furnace such as employed for the treatment of glass or metal; and is especially valuable in connection with the heat treatment of shapes, sheets, plates, etc.

Combustion control in furnaces involves a number of complex and inter-related factors. The problems that give rise to these factors are based primarily upon the question of a practical and economical variation of the intensity and/or characteristics of a flame in accordance with different stages of treatment, such as heat treatment, in accordance with the characteristics of the particular material being treated, as well as in accordance with the type of fuel gas and/or oxygen containing gas available for utilization. Then, too, the control is preferably such that the cracking or breaking down of hydrocarbons present may be accomplished as desired.

Another problem is the proper propagation and diffusion of the flame throughout the furnace, regardless of changes of the type or the characteristics of the flame, to insure a uniform desired heating effect upon the material being treated.

Another factor has been to obtain the maximum conservation of energy or velocity of flow of the fluids or gases utilized by suitably directing and proportioning the gases involved in obtaining a desired combustible mixture.

And, in view of the above considerations, it has been an object of my invention to provide a new and improved method of controlling combustion in a furnace.

Another object of my invention has been to provide new and improved apparatus for carrying out such a method of combustion control.

Another object of my invention has been to provide a flexible, practical, and simple form of combustion control for furnaces.

A further object has been to devise a combustion control that will provide a substantially constant ratio of fuel gas to air irrespective of the character or type of flame.

A still further object of my invention has been to devise a simple control for effectively varying the flame in a furnace from an intense-hard to a luminous-soft type as desired.

These and many other objects of my invention will appear to those skilled in the art in view of

the drawing, the description thereof, and the appended claims.

In the drawing:

Figure 1 is a vertical section in elevation of a device constructed in accordance with the principles of my invention in association with a furnace opening.

Figure 2 is an end section in elevation taken along the line II—II of Figure 1;

Figure 3 is a section taken along the line III—III of Figure 1 showing a construction of a detail of the device; and

Figure 4 is a view similar to Figure 2, but is reduced and shows a modified arrangement.

For the purpose of illustrating my invention, I have shown a casing or a housing 10, preferably of metal, mounted in the opening of a furnace 30 and having inspection doors 10a and 10b. The furnace 30 may be of any suitable form or construction, and as shown, includes inner wall portions 31 and outer wall portions 32 of refractory material. Metal sheets 33 are mounted over the outer refractory wall portions 32 and are adapted to receive mounting brackets 11 extending from the housing 10. The brackets 11 are secured to the furnace 30 by means of bolts 11a. The furnace also has mouth refractory portions 34 adjacent the fuel feed opening therein that are preferably mounted in a cooperative relationship with respect to upper and lower passageways in the device 10.

The housing of the device 10 is, as shown, divided into two chambers 13 and 14 by a metal partition member 12. The lower chamber 13 is provided with a fuel gas inlet 15 having a suitable valve 16 for controlling the supply of fuel gas thereto. A refractory member or group of members 17 is positioned in the casing 13 between the opening in the casing 10 and adjacent the opening in the furnace 30 in such a manner as to substantially align with the refractory members 34. The member 17 is provided inwardly of the chamber 13 with inclined streamlined ends 18. As shown particularly in Figure 2, the refractory member 17 is preferably provided with a single 45 passageway 19, but as shown in Figure 4, it may have a plurality of passageways 19' where necessary in larger constructions. The passageway 19 connects the chamber 13 with the opening in the furnace 30.

The partition 12 extends toward the opening in the casing 10 of the device to provide a support shelf for an upper refractory member or construction 20 having one or more members, and preferably having at least two spaced-apart and 55

vertically separated passageways between the chamber 14 and the furnace 30. The lower passageway 21 is downwardly inclined and somewhat streamlined adjacent its outer end to direct 5 the oxygen-containing gas or air downwardly upon the fuel gas from the chamber 13. This produces a superimposed layer of an oxygen containing gas, such as air, upon the fuel gas; and, since both gases have substantially the same direction of flow, there will be a desired type of 10 turbulence and a maximum utilization of energy of flow to produce an intense hard flame. The gases are thus mixed adjacent the furnace opening with a minimum of turbulence and the intense flame produced is shorter under same pressure conditions than the luminous flame. The upper passageway or passageways 22 of the construction 20 directs fluid flow outwardly in a substantially parallel path with respect to the flow 15 through the passageway 19 and, initially, with respect to the flow through the passageway 21. The flow is continued outwardly in the same path which is, of course, spaced-apart and above the paths of flow through the passageways 19 and 22. 20 By reason of the separation between the path of flow of the fuel gas from the chamber 13, the flow through the passageway 22 from the chamber 14 produces a highly luminous, long, soft, 25 blanket flame of low intensity. Also, it will be noted that the flow outwardly into and through the furnace is in a rectangular blanket-like longitudinal path substantially parallel to the flow of the fuel gas through the passageway 19.

When I speak of a gas containing oxygen, it 30 should be understood that I have reference to any suitable gas, such as stack gas, oxygen, air, or various mixtures of gases, including mixtures of inert as well as hydrocarbon gases containing a gas suitable for aiding combustion of the fuel 35 gas; I prefer air for ordinary installations. It should also be noted that when I speak of fuel gas, I have reference to any suitable form of gas, and it may be preheated, and may also contain oxygen, below the limits of inflammability. The 40 fuel gas may also contain inert as well as active constituents, including hydrocarbons which are to be cracked.

Although as intimated above, I prefer to utilize a single connected passageway for each of the 45 layers 19, 21, and 22, it will be apparent that a plurality of spaced-apart passageways may be employed where necessary in larger constructions, see Figure 4. The blocks 20, 17, 18, may also be of one-piece or of many-part construction. However, a multi-part construction should be properly "pointed", cemented, or closed off; and, if a 50 plurality of passageways are provided, I preferably align those of one layer with those of the other layers, see Figure 4, and preferably provide substantially the same size of openings, although 55 different sizes may be employed to produce desired effects.

In carrying out the present invention, the applicant controls flame characteristics in a furnace by varying the flow through the alternate passageways 21 and 22, or in other words, by varying the layer thicknesses or the proportion of the gases or fluids passed therethrough. The applicant preferably varies the flow in such a manner that the area of flow will be the same, and thus, that the quantity or volume of gas supplied 60 from the chamber 14 may be the same regardless of the amount of gas or the thickness of the layer of gas through a particular one of the alternate passageways. Valves 16 and 36, of course,

may be operated to control the supply of fuel and air gases to the chambers 13 and 14, respectively. This prevents a throttling action, a reduction and loss of energy, a change of ratio of air to fuel gas, and particularly, a loss of velocity energy, and 5 also enables the carrying out of an efficient and effective burning action in the furnace without producing dangerous mixtures and causing heavy encrustations of soot, etc., therein, as well as upon the materials being treated or melted. The 10 size or area of opening in the passageways 21 and 22 is preferably equal or substantially the same, although desired proportionate sizes and/or areas may be provided between these two passageways as well as between them and the passageway 19. 15

For the purpose of controlling the flow between the chamber 14 and the furnace 30, the applicant has shown a vane-like valve 24. A curvilinear valve plate 25 is preferably mounted over inner end portions of the refractory construction 20 to provide an effective valve surface; it is secured to the housing 10 and has openings therein corresponding to the passageways 21 and 22.

The vane 24 is secured to or keyed upon a turnable or rotatable shaft 25a that is journaled in 25 bearings 26 on the casing 10. An operating arm 27 is shown keyed to the shaft 25a and connected to a weighted chain device 28 for actuating the vane 24. It will appear that the vane 24 moves in a radial path and automatically cleans the valve 30 plate surface 25 in its movement. It may completely shut off one of the alternate passageways 21 or 22 and may also provide a proportionate flow through each of them. In this way, the intensity 35 and/or characteristics of the flame may be varied within wide limits. The bearings 26 have suitable packing glands. It will be apparent from the above description that a movement of the valve vane 24 from a position closing off passageway or 40 path 21 to a position closing off passageway 22 will produce a variation in the spacing of the paths of flow of the oxygen gas with respect to the path of flow of the fuel gas through 19.

A conduit 35 is connected to the chamber 14 to 45 supply the oxygen containing gas thereto and may have a suitable form of valve 36 mounted therein.

Although I have shown a preferred form of apparatus for carrying out the principles of my invention, it will be apparent to those skilled in 50 the art that many other suitable forms may be employed without departing from the spirit and scope thereof. Applicant prefers to suitably segregate, direct, and control the path of flow of the fuel gas, and to separate the oxygen containing 55 gas into at least two alternate and spaced-apart or stratified layers that have a controllable thickness or stratification and a suitable direction of flow with respect to the fuel gas.

Thus, it will be apparent that many other combinations, modifications, additions, subtractions, and/or inter-relationships of mechanisms may be employed to carry out my invention as indicated by the appended claims.

I claim:

1. In a method of controlling the intensity and other characteristics of a flame in a furnace, the steps of introducing a fuel gas into the furnace in a substantially uni-directional rectangular path, flowing an oxygen-containing gas in a substantially parallel path spaced apart with respect to the flow of said fuel gas, and then without throttling either gas, directing the oxygen-containing gas downwardly in a superimposed relationship upon the fuel gas while maintaining the ultimate 75

direction of flow of the two gases substantially the same.

2. In a method of controlling flame characteristics in a furnace, the steps of initially flowing a fuel gas and a gas containing oxygen in substantially parallel and spaced apart paths, and then without throttling either gas, directing one of the gases into a superimposed relationship with respect to the other of the gases without substantially changing their general direction of flow.

10 3. In a method of controlling flame characteristics in a heating furnace, the steps of flowing a fuel gas in a suitable path into the furnace, flowing a gas containing oxygen along two paths into the furnace, and directing one of the paths of the gas containing oxygen downwardly upon the path of flow of said fuel gas.

15 4. In a device for controlling combustion in a furnace, a suitable casing mounted adjacent an opening in the furnace, a partition dividing said casing into a pair of chamber portions, one of said chamber portions having an inlet for a gas containing oxygen and the other of said chamber portions having an inlet for a fuel gas, and means 20 mounted in said casing adjacent the opening in said furnace for directing fuel gas from one of said chambers into the furnace and for directing the gas containing oxygen from the other of said chambers into said furnace, said means having 25 portions arranged and constructed to separate the flow of said gases and to provide stratified layers of gases within the furnace, means dividing the flow of one of said gases into two paths, and means variably proportioning quantity flow of 30 such gas between the two paths.

35 5. In a device for controlling combustion in a furnace, a suitable casing mounted adjacent an opening in the furnace, a partition dividing said casing into a pair of chamber portions, one of said chamber portions having an inlet for a gas containing oxygen and the other of said chamber portions having an inlet for a fuel gas, means 40 mounted in said casing adjacent the opening in said furnace for directing fuel gas from one of said chambers into the furnace and for directing the gas containing oxygen from the other of said chambers into said furnace, said means having portions constructed and arranged to separate the flow of said gases and to provide stratified layers 45 of gases within the furnace, and valvular means for controlling quantity flow of at least one of said stratified layers of gas without substantially changing total quantity flow of the gases.

6. In a device for controlling combustion in a furnace having a suitable feed opening therein, a casing mounted in a cooperating relationship with respect to the opening in the furnace, said casing having two refractory portions, each of said refractory portions having fluid passageways connecting the feed opening in the furnace with said chamber portions, said refractory materials having portions arranged and constructed to provide spaced-apart layers of gaseous flow into the furnace, and a valve for controlling the quantity of 55 gaseous flow through individual passageways while maintaining the total quantity of flow into the furnace at substantially the same value.

7. In a combustion controlled device adapted to control flame propagation in a furnace having a suitable feed opening therein, a casing adapted to be mounted over the feed opening, a partition dividing said casing into a pair of fluid chambers, one of said fluid chambers having a supply of fuel gas connected thereto, the other of said chambers having a supply of the gas containing oxygen

connected thereto, refractory members interposed between each of said chambers and the feed opening of the furnace, said refractory members having portions mounted in a spaced-apart relationship with respect to each other and providing fluid passageways between said chambers and the furnace, said refractory members being constructed and arranged to provide at least two spaced-apart paths of flow of fluid from the oxygen containing gas chamber, and a valve operably associated with 10 the refractory members in said last-mentioned chamber for varying the flow of gas through each of said spaced-apart paths of fluid flow, said valve being constructed and arranged to provide the same area of passageway between the furnace and 15 said chamber regardless of the quantity of fluid flowing through one of said spaced-apart paths.

8. In a combustion control device adapted to control flame propagation in a furnace having a suitable feed opening therein, a casing adapted to 20 be mounted over the feed opening, a partition dividing said casing into a pair of fluid chambers, one of said fluid chambers having a supply of fuel gas connected thereto, the other of said chambers having a supply of gas containing oxygen connected thereto, refractory members interposed between each of said chambers and the feed opening of the furnace, said refractory members having portions mounted in a spaced-apart relationship with respect to each other and providing fluid 25 passageways between said chambers and the furnace, said refractory members being constructed and arranged to provide at least two spaced-apart paths of flow of fluid from the oxygen containing gas chamber, and a valve operably associated with 30 the refractory members in said last-mentioned chamber for varying the flow of gas through each of said spaced-apart paths of fluid flow, said valve being constructed and arranged to provide the same area of passageway between the furnace and 35 said chamber regardless of the quantity of fluid flowing through one of said spaced-apart paths, said refractory members adjacent one of said spaced-apart paths being constructed and arranged to direct the fluid containing oxygen 40 downwardly upon the combustible fluid as it enters the furnace.

9. In a combustion control device adapted to control flame propagation in a furnace having a suitable feed opening therein, a housing adapted 50 to be mounted adjacent the opening in the furnace, a partition dividing said housing into at least two chamber portions, one of said chamber portions being provided with a gas containing oxygen, the other of said chamber portions being 55 provided with a fuel gas, members associated with said housing having fluid passageways therein connecting each of said chambers with the opening in the furnace, a valve plate mounted upon the portion of said members mounted in the 60 chamber containing the oxygen gas, a radially turnable valve vane operably mounted in said last-mentioned chamber, said valve vane being constructed and arranged to move over said valve plate and over the passageways in adjacent portions 65 of said members for controlling the flow of the gas containing oxygen therethrough, and means associated with said vane for moving it from one position to another for regulating said flow, and additional means for controlling flow of 70 fuel gas to said fuel gas chamber and for controlling flow of the oxygen containing gas to said oxygen containing gas chamber.

10. In a device for controlling combustion in a furnace, a housing adapted to be mounted ad-

1 jacent an opening in the furnace, a partition
2 dividing said housing into chamber portions, one
3 of said chamber portions having an inlet for a gas
4 containing oxygen and the other of said chamber
5 portions having an inlet for a fuel gas, means in
6 said housing adapted to be positioned adjacent the
7 opening in the furnace for directing fuel gas from
8 one of the chamber portions into the furnace and
9 for directing gas containing oxygen from another
10 of the chamber portions into the furnace, said
11 means having a portion for directing at least one
12 of said gases along a pair of paths in the direction
13 of the furnace opening, and means operably as-
14 sociated with said last mentioned means for vary-
15 ing flow of the particular gas along said pair of
16 paths in such a manner that the total flow area
17 for such gas in the direction of the opening in the
18 furnace is maintained substantially constant.

19 11. In a device for controlling combustion in a
20 furnace, a suitable housing adapted to be mounted
21 adjacent an opening in the furnace, a partition
22 dividing said housing into chamber portions,
23 one of said chamber portions having an inlet for
24 a gas containing oxygen and another of said
25 chamber portions having an inlet for a fuel gas, a
port connecting said fuel gas chamber with the
furnace opening, a pair of ports connecting said
oxygen containing gas chamber with the furnace
opening, and means operably associated with said
pair of ports for varying the flow of the oxygen
containing gas therethrough without changing
the total port area.

26 12. In a device for controlling flame character-
27 istics in a furnace, means for flowing a fuel gas
28 into the furnace, means providing at least two
29 paths of flow into the furnace of a gas containing
30 oxygen, and means for varying the quantity of
31 flow of the gas containing oxygen in each of said
32 two paths and for maintaining the total quantity
33 of flow of said gas at substantially the same value.

34 13. In a device as defined in claim 12, means for
35 directing one of the paths of the gas containing
36 oxygen downwardly upon a path of flow of said
37 fuel gas.

38 14. In a device for controlling flame character-
39 istics in a furnace, means for introducing a fuel
40 gas into the furnace, means for introducing gas

41 containing oxygen into the furnace, means pro-
42 viding two alternate paths for introducing one of
43 said gases into the furnace, and means for propor-
44 tioning the gas flow between said two alternate
45 paths to vary the flame from a luminous type to
an intense type.

46 15. In a method of controlling flame character-
47 istics in a furnace, the steps of introducing a fuel
48 gas into the furnace in a substantially uni-directional
49 path, initially introducing a gas containing 10
50 oxygen into the furnace in a substantially parallel
51 path with respect to the path of the fuel gas, and
52 then without throttling, directing flow of one of
53 the gases downwardly upon the path of flow of the
54 other gas. 15

55 16. In a device for controlling flame character-
56 istics in a furnace, means for separately introduc-
57 ing stratified streams of a gas containing oxygen
58 and of a fuel gas into the furnace, and means for
59 varying the quantity flow of at least one of the
60 streams in accordance with the flame character-
61 istics desired without substantially changing total
62 quantity flow of the gas.

63 17. In a device for controlling the intensity and
64 other characteristics of a flame in a furnace, 25
means for introducing a fuel gas and a gas con-
65 taining oxygen into the furnace in substantially
66 parallel flow paths, and valvular means for vary-
67 ing spacing of the paths of flow with respect to
68 each other.

69 18. In a device for controlling the intensity and
70 other characteristics of a flame in a furnace,
71 means for introducing a fuel gas and a gas con-
72 taining oxygen into the furnace in substantially
73 parallel flow paths, valvular means for varying the
74 flow of one of such gases between two substan-
75 tially parallel paths and for maintaining the same
76 ratio of fuel gas to oxygen-containing gas flow.

77 19. In a device for controlling the intensity and
78 other characteristics of a flame in a furnace,
79 means for introducing a fuel gas and a gas con-
80 taining oxygen into the furnace in substantially
81 parallel flow paths, and means for varying spacing
82 and direction of the flow of such gases with re-
83 spect to each other.

HENRY WILBUR PARET, JR.
